UNITED STATES PATENT OFFICE.

FREDERICK W. LOVELL, OF CLEVELAND, OHIO, ASSIGNOR TO THE McMYLER INTER-STATE COMPANY, OF CLEVELAND, OHIO, A CORPORATION OF OHIO.

GRAB BUCKET.

Application filed January 26, 1921. Serial No. 440,214.

To all whom it may concern:

Be it known that I, FREDERICK W. LOVELL, a citizen of the United States, residing at Cleveland, in the county of Cuyahoga and State of Ohio, have invented a certain new and useful Improvement in Grab Buckets, of which the following is a full, clear, and exact description.

This invention relates to a grab bucket, and has for its chief object to provide a bucket characterized by an unusual degree of ruggedness and durability, which has a powerful closing action in picking up a load, and which by its construction is well adapted for use in unloading boats, or under other circumstances which require that the bucket be lowered through a more or less restricted space such as a hatch opening, the construction of the upper part of the frame or housing of the bucket being such as to make it easy to withdraw the bucket through the restricted space and to minimize liability of shocks between the bucket and some overhead member as the bucket is elevated.

The invention may be briefly summarized as consisting in certain novel details of construction, and combinations and arrangements of parts which will be described in the specification and set forth in the appended claims.

In the accompanying sheets of drawings wherein I have shown an embodiment of the invention which operates with very high efficiency, Figs. 1 and 2 are perspective views of my improved grab bucket, Fig. 1 showing the jaws partially open, and Fig. 2 showing them closed; Fig. 3 is a side view of the bucket showing by full lines the jaws in closed position and by dotted lines in open position; Fig. 4 is a plan view of the top of the bucket; Fig. 5 is an end or side view with the bucket turned ninety degrees from the position shown in Fig. 3; Fig. 6 is a transverse sectional view substantially along the line 6-6 of Fig. 5, looking in the direction indicated by the arrows; and Fig. 7 is a view on a reduced scale showing one of the bucket jaws.

My improved grab bucket includes a rigid frame or housing which in the main is in the form of a truncated pyramid, two of the sides sloping inward from the bottom to the top, and the other two sides being parallel for a portion of their height, and at a

certain point sloping inward toward the top. This inward sloping or general pyramidal form makes it virtually impossible for the bucket to get other than a glancing blow when the bucket is being elevated through a hatch opening or other restricted space.

The frame at the top has a cast steel cap 10 which receives upper sheaves 11 mounted on a pin or stud 12, and extending down from this cap at the corners of the frame are four angles 13. These diagonally disposed corner angles are connected by structural members in the form of plates and angles such as indicated at 14, so as to provide an extremely rigid and strong frame or housing, well adapted to accommodate the operating parts of the bucket.

Two opposite sides of the housing, these being the sides between which the jaws swing, are parallel from their lower portions up to a point just beneath the upper sheaves 11 to accommodate a sliding lower sheave holder as will subsequently appear, and then these sides taper off toward the top as also ready explained. The lower portions of these sides just referred to, extend downward in the form of a V, as shown at 15, the V-shaped portions extending below the lower ends of the corner angles 13, and at the top 85 of the V-shaped portions of these sides outwardly bowed truss-like plates 16 are provided; these plates extending across the sides from one corner angle to the other so as to stiffen and brace the downward extending 90 V-shaped portions.

These sides are further stiffened by external steel rails 17 which extend from the top of the frame down through and at right angles to the bowed plates 16 to the apices 95 of the V-shaped portions 15. These rails serve not only to stiffen the frame but take the thrust or blow if the sides strike an obstruction.

The jaws of the bucket which are shown 100 at 18, have their upper outer portions connected by cast steel swinging links 19, to the four lower corners of the frame adjacent the lower ends of the corner angles 13, and the upper inner portions of these jaws are 105 further connected by arms 20 to opposite ends of a vertically movable jaw operating member and lower sheave holder 21, which after the manner of a cross-head slides up and down in the housing. This member 21 110

is substantially semi-cylindrical in form with a rounded bottom and open top, and it carries a plurality of lower sheaves 22 mounted on a pin 23 in diagonally disposed plates 24 extending across the inside of the member 21 as shown in Fig. 6. It might be stated at this point that the upper and lower sheaves 11 and 22 are skewed, as is customary in buckets of this kind, so that the on-running and off-running portions of the operating rope will be at the center plane of the bucket.

The ends 25 of the jaw operating member or cross-head 21 have thick center portions 26 provided with vertical guide slots which receive the heads of two oppositely disposed guide rails 27 which are secured to the inner sides of the frame, these guide rails extending from the lower ends or points of the V-shaped portions 15 to the upper limits of the parallel sides, and then for a distance along the inclined portions, as best shown in Figs. 5 and 6. These inner guide rails 27 not only guide the jaw operating member and lower sheave holder 21 in its vertical movement, but assist in strengthening and stiffening the frame. The jaw operating arms 20 are pivoted to the ends of the member 21 on pins 28 which are located on opposite sides 30 of the slides receiving the guide rails 27 as shown in Fig. 6.

Two ropes are utilized in operating this bucket, namely, a holding rope 30 and an opening and closing rope 31. The ends of the holding rope 30 are attached to the middle points of two transverse pins or bolts 32 which pass through the upper cap 10 and through the upper ends of the corner angles 13. The opening and closing rope 31 is reeved back and forth around the upper and lower sheaves 11 and 22, and the on-running and off-running portions of this rope pass between pairs of guide rollers 33 supported by the cap 10, as shown in Figs. 3 and 4, these portions of this rope being in the center plane of the bucket.

The following features of construction with the attendant peculiar movements and relationship of the parts at various positions of the jaws, contribute to the production of a bucket with a powerful and efficient closing stroke. For example, it is important that the links 19 be connected substantially as shown, to the upper outer corners of the jaws. It is to be noted also, that the arms 20 are upwardly inclined when the bucket is closed, and that the points of connection of these arms and the cross-head are above the links when the bucket is closed, but when the bucket is full open the arms 20 are downwardly inclined, and the points of connection with the cross-head are below the links, the arms 20 making about the same angle with one another when the bucket is open as when the bucket is closed.

Likewise it is to be noted that when the bucket is closed the links 19 are outwardly inclined from their points of suspension on the frame or housing, and that when the bucket is full open the links 19 are inclined inwardly. The links 19 swing in and out to accommodate the up and down movement of the cross-head 21, and as the cross-head is lowered from its uppermost position, and as the arms 20 approach a position of alignment, the links 19 swing outward, and when the cross-head passes below this position of the arms, the links swing inward. When the cross-head starts upward in the closing movement of the jaws, not only do the lower digging edges of the bucket move inward, but at the same time the upper ends of the jaws move outward somewhat as the links 19 swing outward, so that there is in effect during the initial movement of the jaws, not only an inward swinging, but a rocking movement of the jaws which bring the digging or cutting edges to most effective position for scooping up material.

While I have shown the preferred construction, I do not wish to be confined to the exact details shown, as certain modifications can be made without adversely affecting the efficiency of the bucket.

Having described my invention, I claim:

1. In a grab bucket, a frame having a relatively fixed sheave holder at the top and a lower movable sheave holder in the form of a cross-head, a pair of jaws connected to the frame and having operating arms connected to the cross-head, said frame being in the form of a rigid structure with two opposite sides inclined inward toward the upper sheave holder and two opposite sides having parallel portions on which the cross-head is guided, and inwardly inclined portions above the parallel portions, said relatively fixed sheave holder being mounted within the upper portion of the frame between the last mentioned inwardly inclined side portions.

2. In a grab bucket, a frame in the general form of a truncated pyramid with two opposite inclined sides and two opposite sides parallel for a distance from the bottom, and with upper portions inwardly inclined, a relatively fixed sheave holder within the upper portion of the frame, a lower sheave holder in the form of a cross-head guided for vertical movement on the parallel portions of the last mentioned sides, jaws connected to the frame and having arms connected to the cross-head, and means for operating the cross-head.

3. In a grab bucket, a rigid frame having an upper relatively fixed sheave holder, a lower movable sheave holder in the form of a cross-head guided for vertical movement on two opposite sides of the frame, a pair of jaws connected to four lower cor-

ners of the frame and having operating arms connected to the cross-head, the two sides of the frame on which the cross-head is guided having extensions projecting downwardly beneath the points of connection with the jaws, and transverse outwardly bowed stiffening members extending across said sides at the top of said extensions.

4. In a grab bucket, a rigid frame having an upper relatively fixed sheave holder, a lower movable sheave holder in the form of a cross-head guided for vertical movement on two opposite sides of the frame, vertical cross-head guides upon the inner faces of the sides of the frame, a pair of jaws connected to four lower corners of the frame and having operating arms connected to the cross-head, the two sides of the frame on which the cross-head is guided having extensions projecting downwardly beneath the points of connection with the jaws, and vertically disposed stiffening members extending centrally from the upper end of the frame down along the outer faces of said sides to the lower portions of said extensions.

5. In a grab bucket, a rigid frame having an upper relatively fixed sheave holder, a lower movable sheave holder in the form of a cross-head guided for vertical movement on two opposite sides of the frame, a pair of jaws connected to four lower corners of the frame, and having operating arms connected to the cross-head, the two sides of the frame on which the cross-head is guided having extensions projecting downwardly beneath the points of connection with the jaws, and vertically disposed members extending centrally down along the inner and outer faces of said sides including the extensions, the inner members forming guides for the cross-head.

6. In a grab bucket, a rigid frame having an upper relatively fixed sheave holder, a lower movable sheave holder in the form of a cross-head guided for vertical movement on two opposite sides of the frame, vertical cross-head guides upon the inner faces of the sides of the frame, a pair of jaws connected to four lower corners of the frame and having operating arms connected to the cross-head, the two sides of the frame on which the cross-head is guided having extensions projecting downwardly beneath the points of connection with the jaws, transverse stiffening members extending across said sides at the top of said extensions, and vertically disposed stiffening members extending centrally from the top of the frame down the sides to the lower ends of the stiffening members.

7. A grab bucket comprising a housing having jaws connected to the lower part thereof, an upper sheave holder within the housing, a movable lower sheave holder guided in the housing for vertical movement

and connected to the jaws to operate them, said housing comprising downwardly and outwardly inclined corner members connected together to form a rigid frame-work.

8. A grab bucket comprising a housing having jaws connected to the lower part thereof, an upper sheave holder, a movable lower sheave holder guided in the housing for vertical movement and connected to the jaws to operate them, said housing comprising downwardly and outwardly inclined corner members connected together to form a rigid frame-work, two of the sides having guides for the cross-head and provided at the bottom with extensions between which the jaws swing, said sides being braced externally by transverse and vertically disposed members.

9. In a grab bucket, a housing having an upper sheave holder, a lower sheave holder movable vertically in the housing and guided thereby, a pair of jaws having arms connected to the ends of the lower sheave holder and links connected to the lower outer portions of the housing and connected to upper outer corners of the jaws.

10. In a grab bucket, a housing having an upper sheave holder, a lower sheave holder movable vertically in the housing and guided thereby, a pair of jaws having arms connected to the ends of the lower sheave holder, and links connected to the lower outer portions of the housing and connected to upper outer corners of the jaws, the links being inclined outwardly from the housing to the jaws when the latter are closed and inclined inwardly from the housing when the jaws are full open.

11. In a grab bucket, a housing having an upper sheave holder, a lower sheave holder movable vertically in the housing and guided thereby, a pair of jaws, links connecting the jaws to the lower outer portions of the housing, and jaw operating arms rigidly connected to the jaws and pivotally connected to the lower sheave holder, said arms being at substantially right angles to the direction of movement of the lower sheave holder when the jaws are partially open and being inclined downwardly from the jaws when the latter are full open.

12. In a grab bucket, a housing having an upper sheave holder, a lower sheave holder movable vertically in the housing and guided thereby, a pair of jaws, links connecting the jaws to the lower outer portions of the housing, and jaw operating arms rigidly connected to the jaws and pivotally connected to the lower sheave holder, said arms inclining upwardly from the jaws to the lower sheave holder when the jaws are closed and inclining downwardly from the jaws to said sheave holder when the jaws are full open.

13. In a grab bucket, a housing having an upper sheave holder, a lower sheave holder

movable vertically in the housing and guided thereby, a pair of jaws, links connecting the jaws to the lower outer portions of the housing, and jaw operating arms rigidly connected to the jaws and pivotally connected to the lower sheave holder, said arms being inclined upwardly and inwardly when the jaws are closed and being inclined downwardly when the jaws are full open, and in both instances 10 making substantially the same angle with each other.

14. In a grab bucket, a housing having an upper sheave holder, a lower sheave holder movable vertically in the housing and guided

thereby, a pair of jaws, links connecting the 15 jaws to the lower outer portions of the housing, and jaw operating arms rigidly connected to the jaws and pivotally connected to the lower sheave holder, the points of connection of the arms with the lower sheave holder 20 passing from a position above to a position below the points of connection of the links with the jaws when the latter are moved from closed to full open position.

In testimony whereof, I hereunto affix my 25 signature.

FREDERICK W. LOVELL.
